US00D801375S

(12) **United States Design Patent** (10) Patent No.: **US D801,375 S**
(45) Date of Patent: **** Oct. 31, 2017**

(54) **DISPLAY SCREEN WITH GRAPHICAL USER INTERFACE**

(71) Applicant: **MITSUBISHI ELECTRIC CORPORATION**, Tokyo (JP)

(72) Inventors: **Satoshi Yamazaki**, Tokyo (JP); **Ayako Nagata**, Tokyo (JP)

(73) Assignee: **Mitsubishi Electric Corporation**, Tokyo (JP)

(**) Term: **15 Years**

(21) Appl. No.: **29/604,527**

(22) Filed: **May 18, 2017**

CLAIM

The ornamental design for the display screen with graphical user interface, as shown and described.

DESCRIPTION

The FIGURE is a front view of display screen with graphical user interface showing our new design.

The outermost broken line rectangle illustrates a display screen and forms no part of the claimed design. The remaining broken lines illustrate portions of a graphical user interface and form no part of the claimed design.

1 Claim, 1 Drawing Sheet
